[57] **ABSTRACT**

In the manufacture of a single ended subminiature incandescent lamp, a helically coiled wire filament is bent into a hairpin shape and is mounted on a temporary support while the mandrel on which the wire has been coiled is still within the filament. The filament is then inserted into acid in order to dissolve the mandrel at the apex portion of the filament. The filament is then sealed within a glass envelope.

METHOD OF MANUFACTURING MINIATURE INCANDESCENT LAMPS

BACKGROUND OF THE INVENTION

This invention results to single ended subminiature lamps, the illumination from which relists from a tungsten filament heated to incandescence by flow of electric current therethrough. It especially relates to a method of making such lamps.

Subminiature lamps generally have a filament made of such fine wire that it can only be seen and handled under magnification; thus the coil mount and assembly is done by hand with consequent high costs. The filament is generally made by helically coiling fine tungsten wire on a metal mandrel wire, several times its diameter, in a long continuous length. The coiling is heat treated to set it and is then cut into predetermined filament lengths. The mandrel is dissolved in acid either before or after the cutting step. The filament is then hand mounted on a suitable support and then sealed within a small glass envelope.

It is an object of this invention to provide a method of manufacturing that permits employment of automatic assembly machines, thereby eliminating much of the hand work involved and thereby significantly reducing the cost of such lamp.

THE INVENTION

In the drawing,

FIG. 1 shows a hairpin shaped, mandrel-containing, helically coiled wire filament mounted on a temporary support.

FIG. 2 shows the filament immersed in acid to dissolve the mandrel.

FIG. 3 shows the filament, still mounted on the temporary support, sealed into one end of a glass envelope.

FIG. 4 shows the finished lamp.

In the manufacture of a single ended subminiature incandescent lamp in accordance with this invention, fine tungsten wire 1, generally less than 1 mil diameter, is continuously helically coiled on a wire mandrel 2 of larger diameter. The mandrel 2 is made of a suitable metal, say, nickel, steel or molybdenum, that can be dissolved in an acid that does not readily attack tungsten. In a typical case, the mandrel diameter is 3 or 4 mils.

The coiling-with-mandrel can than be heat treated, if necessary, to set the coiling and is then taken up on a spool in a long continuous length. Next, the coiling is mounted on suitable apparatus where it is unreeled and cut into predetermined lengths. The cut lengths are then bent into a hairpin or U shape and the ends thereof are attached to a suitable temporary support 3. The fact that the mandrel 2 is still within each cut length gives it sufficient bulk to permit the bending and attaching steps to be performed on automatic equipment. The distance between legs of the bent filament at the time of attaching to a suitable support 3 is small enough to permit the filament to be inserted into a tubular glass envelope 7 at the time of lamp assembly while the filament is mounted on said support 3. In a typical case, the distance between legs was about one-sixteenth inch.

The support 3 on which the bent filament is mounted must be suitable to support the filament until the filament is sealed in a glass envelope 7. The support 3 may be a small flat piece of metal to which the ends of the

bent filament are attached, as by welding. In such a case, the metal piece remains outside the lamp envelope 7 and is removed after the filament is sealed in the envelope 7. Or the support may be machine holding blocks in which the legs of the bent filament are clamped. The blocks hold the filament through all operations until after the filament is sealed in the lamp envelope.

After the bent filament has been mounted on the support 3, the filament is dipped in a suitable acid 4 to dissolve the mandrel 2. The mandrel 2 is dissolved in at least the effective lighted length of the filament but not at the portions thereof which are part of the glass-to-metal seal in the finished lamp. Thus, the support 3 is not dipped into the acid 4 and the mandrel 2 is not dissolved in those portions of the filament legs which are not immersed in the acid. The acid may be heated to reduce the time for dissolving the mandrel to a few seconds. Typically, hydrochloric acid is used to dissolve a steel mandrel, while a combination of sulphuric and nitric acids is used to dissolve a molybdenum mandrel.

After the filament is rinsed and dried, it is ready for sealing in a glass envelope 7. The filament is inserted into one end of a small diameter glass tubing 5, typically, Tl or $\frac{1}{8}$ inch diameter, and the end of the tubing is heated to its softening point. The softened end is then squeezed on the legs of the filament to form a hermetic press seal 6. The temporary support 3 remains outside the envelope 7 and is removed after the filament has been sealed in the envelope.

In any case, however, it is important that mandrel 2 remain within that portion of the filament which is embedded in the glass which forms the glass-to-metal seal of the lamp envelope 7. The reason for this is to keep the electrical resistivity of the conductors which are embedded in the glass low, so that they will not overheat during lamp operation which, if overheating occurred, could crack the glass seal. Also, the mandrel may aid somewhat in forming a hermetic seal during the press operation if the filament has high TPI (turns per inch) coiling.

After the filament has been inserted in one end of the glass tubing and sealed there, the tubing is exhausted through the other end and is then heated and tipped off to form the lamp envelope. The tubing at said other end may have been previously tubulated or necked down in diameter to aid in tipping off the lamp.

In an example of a 5 volt 60 milliamper Tl lamp made in accordance with this invention, the filament coiling consisted of 0.6 mil tungsten wire wound on 4 mil molybdenum wire at 650 TPI. The coiling was heat treated at 1,525°C and then cut into lengths of 20 mm. Each cut length was then folded in a hairpin and the ends thereof were welded to a temporary support consisting of a rectangular piece of 4 mil nickel, about 6 mm by 3 mm. The legs of the hairpin were about 1 $\frac{1}{2}$ mm apart. The apex of the hairpin was then inserted into heated sulfuricnitric acid to a depth of about 1 $\frac{1}{2}$ mm for about 5 to 10 seconds to dissolve the molybdenum mandrel therein. After rinsing and drying, the filament, apex first, was inserted into one end of Tl glass tubing, open at both ends. The other end of the glass tubing was connected, by a vacuum tight connection, to exhaust and filling apparatus. The first end of the glass tubing was heated to its softening point and then pressed onto the legs of the filament to form a hermetic press seal. If necessary, the interior of the tubing could

be flushed with a suitable inert gas to prevent oxidation of the filament during press sealing. The other end of the glass tubing was then heated and tipped off while a vacuum was maintained in the tubing. The temporary support was then removed by cutting off the excess length of the filament legs.

The finished lamp had a diameter of about one-eighth inch and an overall envelope length of about 6 mm. The lighted length of the filament was about 2 1/2 mm. The length of the press seal was about 2 1/2 mm and the length of the filament legs protruding outside the press was about 3 mm. The lamp is energized by suitable connection of said legs to a 5 volt power supply.

I claim:

1. In the process of manufacturing a single ended

subminiature incandescent lamp, the steps which sequentially comprise: helically coiling a length of fine tungsten wire on a mandrel wire having a larger diameter; heat treating and cutting the coiling into predetermined lengths; bending each of the cut lengths into a hairpin shape; attaching the ends of the hairpin to a temporary support; dissolving part of the mandrel at the apex end of the hairpin; inserting the hairpin into an open ended glass tube; heating and press sealing one end of the glass tube onto a portion of the legs of the hairpin, said portion still containing mandrel wire; sealing the other end of the glass tube and removing the temporary support to form a finished lamp.
